UNITED STATES PATENT OFFICE.

ALBERT B. CHANCE, OF CENTRALIA, MISSOURI.

DESIGN FOR AN ANCHOR-ROD.

56,118.

Specification for Design. Patented Aug. 24, 1920.

Application filed November 22, 1919. Serial No. 339,954. Term of patent 14 years.

To all whom it may concern:

Be it known that I, ALBERT B. CHANCE, a citizen of the United States of America, residing at Centralia, in the county of Boone and State of Missouri, have invented a new, original, and ornamental Design for Anchor-Rods, of which the following is a specification, reference being had to the accompanying sheet of drawings, forming a part thereof and illustrating the invention.

Figure 1 of the drawings is a side elevation of my new design of anchor rod, and Fig. 2 is another side elevation of the same design, showing the edge of the anchor rod eye.

The anchor rod of this invention consists of a rod portion having a pointed end adapted to be driven into the earth and to

engage an anchor plate for holding the latter, the upper end of the rod having an eye formed thereon for accommodating a guy strand, the upper end of the eye portion being thickened or reinforced preferably as shown, to prevent injury to the eye portion in driving the rod.

I claim:

The design for an anchor rod substantially as shown and described.

As inventor of the foregoing I hereunto subscribe my name this 26 day of December, 1918.

ALBERT B. CHANCE.
